Specification of Letters Patent.

Patented Feb. 3, 1920.

Application filed June 3, 1918. Serial No. 238,006.

To all whom it may concern:

Be it known that I, MAGNUS H. JOHANSON, a subject of the King of Sweden, and a resident of the city of Rochester, in the 5 county of Monroe and State of New York, have invented a new and useful Improvement in Checkwriters, of which the following is a specification.

This invention relates to printing or 10 marking apparatus of the kind known as check protectors and refers more particularly to the kind of the machines constructed to emboss or disrupt the fibers of the paper printed upon in order to permit ink to be incorporated with the fibers and thereby render alteration difficult.

One object of the invention is to provide 20 a simple, compact machine capable of printing numbers or amounts having varying numbers of digits, with different captions or descriptive words printed in connection therewith in such a way as to make it impossible to raise the number or amount by insertion of a digit in a higher denominational order than used in printing the original amount.

Another object is to provide an improved 30 mechanism for bringing a printing couple together with sufficient force to emboss or disrupt the fibers of the paper.

Still another object of the invention is to 35 provide an improved inking mechanism whereby ink is applied to the type to be printed from as an incident to and preliminarily to bringing the printing couple together.

With these and incidental objects in view 40 the invention consists in certain novel features of construction and combinations of parts, an illustrative embodiment of which is shown in the drawings accompanying and forming a part of this specification, the novel features of the invention being pointed out in appended claims.

45 Of said drawings:

Figure 1 is a top plan view of the assembled machine.

Fig. 2 is a left side elevation of the assembled machine.

50 Figs. 3, 4 and 5 illustrate impressions made by the machine and are intended particularly to show how the descriptive word or designation is printed in close juxtaposition to the left hand digit regardless of the 55 number of digits in the number or amount.

Fig. 6 is a section on the line 6—6, Fig. 10, with some of the parts broken away to expose others to view and with the various parts in the positions they assume when the type are engaged with the platen.

60 Fig. 7 is a view of mechanism at the left hand side of the machine and illustrates particularly the impression operating mechanism, the inking mechanism and details of the word type carrier mechanism.

65 Fig. 8 is a detail of the mechanism for shifting and limiting the shifting movement of the word printing type carrier and the alining mechanism for said carrier.

Fig. 9 is a section on the line 9—9, Fig. 2, 70 looking in the direction indicated by the arrows.

Fig. 10 is a section on the line 10—10, Fig. 2, looking in the direction of the arrows and having the type carrier setting elements adjusted to their uppermost position.

75 The machine shown in the drawings has a stationary base with a pivoted head movable relative to the base to take printing impressions. Mounted in the pivoted head are 80 type carriers provided with digit type and having handles whereby the carriers may be adjusted to present desired digits at a printing line. The units of dollars and the cents carriers are, when adjusted to what may be 85 termed their normal position, constructed to print zeros if an impression should be taken, while the segments for printing denominations higher than units of dollars are, when in said normal position, so constructed that 90 there is a clearance at the printing line.

At the left of the highest order digit type carrying element is a rotatable type carrier 95 provided with type for printing different words such as "Pay", "Cancelled" and "Certified". Associated with this rotatable type carrier is a knob and other connections whereby the type carrier may be rotated to set the desired word at the printing line.

100 Fixed at the printing line is a platen and when the operation to bring the type into printing engagement with the platen is commenced, the rotatable type carrier is shifted laterally of the machine so as to position it for the selected word to be printed 105 adjacent the highest digit of the amount. This shifting movement is imparted at the first movement of an invariably moved impression taking operating handle through a resilient connection which permits stop- 110

ping the shifting movement of the type carrier at different points in the stroke of the handle. Stops are provided for limiting differentially the shifting movement of the 5 word type carrier so as to relieve the digit type carriers from side stress, but, at the same time, the shifting type carrier is engaged with the first type carrying segment from the left which has been adjusted to 10 printing position thereby giving the shifted type carrier a better support when the impression is taken. When in shifted position ready to print, the shifting type carrier is engaged with the clearances in the 15 unadjusted type carriers thereby preventing adjustment of those type carriers during a printing operation.

The impression taking handle is of the 20 oscillating type and has rigid therewith segments meshing with segments formed on stationary members. The two sets of segments coöperate in such a way that oscillation of the handle will give a very heavy impression such as is necessary to emboss or 25 disrupt the fibers of tough strong paper, this construction being peculiarly adapted to machines of the type shown and described.

Ink is applied to the type by an ink roll 30 which is moved across the face of the type at printing position before the impression is taken. As it moves across the type, the roll is resiliently pressed into engagement firmly enough to insure the application of plenty of ink. The resilient feature mentioned, 35 however, prevents the roller from disturbing the setting of the type and at the same time causes the roll to accommodate itself automatically to differences due to wear so that the type will be properly inked even 40 after the ink roll has seen long service.

Described in detail and with reference to the drawings, the machine comprises a base 45 designated by the numeral 20 in the different figures, the top of this base forming a printing bed. The bottom of the base is closed by a plate 21 having formed thereon lugs 22, Fig. 6, engaging ribs 23 formed on the rear of the base. Spring fingers 24 fastened to the plate 21 coöperate with suitable ribs or inwardly extending projections 25 formed in the front of the base to latch the plate 21 in position.

Fastened on the under side of the base 20 is a trough-shaped element 26 containing a 55 platen bar 27 extending far enough through a slot in the base top to bring its upper surface in position to coöperate with type before referred to and described in detail later on. The platen bar 27 is held in position by screws 28 (see also Fig. 10) extending upward through the lower part of the platen support 26 through holes made oblong to permit adjustment of the platen laterally of the machine to secure correct 60 operating relation between the platen and

type. Fastened to the top of the base 20 at either side of the machine, are elements comprising portions 31, Figs. 6 and 9, fastened to the top of the base and forwardly extending arms 32. The arms 32 form part of the 70 impression taking mechanism and have other functions as will appear later on.

Mounted in the arms 32 is a rod 33. Pivoted on this rod is a casing comprising side plates 34 and 35 serving as supports for different shafts and bars extending from side to side of the machine. The top of the pivoted casing is closed by a plate 36 having lugs 37, Fig. 2, by which it may be fastened to the side plates 34 and 35. The front of 80 the pivoted casing carries an index plate 38, also a door 41 hinged on a cross plate 42 forming part of the casing and provided to give access to the interior, as, for example, when it is necessary to replenish the 85 supply of ink.

Journalized in the side plates 34 and 35 of the pivoted head is a rock shaft 44. Loose on this rock shaft is an element 45 with a rearwardly extending portion similar to the one shown at 46, Fig. 6, and having an open slot engaging a rod 47 fastened in the side plates 34 and 35. The downwardly extending portion of the frame or casting 45 is provided with type 48, Fig. 10, to print 95 the word "Cents". Pivoted on the shaft 44 to the left of the element 45 are the units and tens of cents type carriers 51 and 52 each carrying type to print the digits 0 to 9 and to the left of the carrier 52 is an element 100 comprising side arms 53 loose on the shaft 44 and having rearwardly extending portions 54 engaged with the rod 47 in the same way as the arm 46, Fig. 6. The lower ends of the arms 53 are connected by a bar 105 55 carrying type 56, Fig. 10, to print the word "Dollars". Pivoted on the shaft 44 to the left of the "Dollars" printing type are carriers 61 to 65 inclusive. The type carriers 61 to 65 are to print digits representing dollars, each carrying a set of digits 0 to 9, so it is apparent that these type carriers, in connection with the cents digit type carriers 51 and 52, give the illustrative machine a capacity of 99,999.99. 115

Rigid with each of the type carriers 51, 52 and 61 to 65 inclusive are handles 66 extending through slots in the index plate 38. The index plate 38 is, as shown in Fig. 1, provided with digits serving to guide the operator in moving the handles and thereby the type segments to position the desired digits at a printing line. 120

Attached to the sides of the handles 66 are indicators 67, Figs. 1 and 9, each bearing the numerals 0 to 9 visible through small openings 68 in the index plate 38 so that the operator may readily see the amount the machine has been prepared to print. The numerals on the indicators 67 may, of course, 125 130

be in some distinctive color so that there will be no chance for confusion with the numerals on the index plate 38. By referring to Fig. 6, it will be apparent that 5 by adjusting the handles 66 any desired type on the type carriers rigid with the handles may be set in position to coöperate with the platen bar 27 previously mentioned. Pawls 71 pivoted on the rod 47, are held 10 by springs 72 in engagement with notches 73 formed in the type carrying elements to aline the type. Spacing collars, not designated by numerals, on the shaft 44 hold all of the parts on said shaft in correct lateral 15 position.

The words "Pay", "Certified" and "Cancelled" shown in Figs. 3, 4 and 5, are printed from type on a carrier 74, Figs. 6, 7 and 10. As shown in the two figures first mentioned, 20 the type carrier 74 has three portions each of which carries type for printing one of the three words designating or describing the amount. The type carrier 74 is integral with a sleeve 75, Fig. 10, and 25 a portion 76 comprising two peripheral flanges, the purpose of which will be clear farther on. The portion 76 has an axial opening concentric to a shaft 77 rotatably supported in the side plate 34 and an auxiliary plate 771 supported at its upper end by the shaft 44. The interior of the sleeve 75 and type carrier 74 is non-circular to co-operate with a non-circular head 78. The head 78 is part of an element having a portion 79 inserted in a hole in the end of the shaft 77 and held in position by a dowel pin 80. It is apparent from this construction that any rotative movement of the shaft 77 will carry the type carrier 74 along while 40 the type carrier is free to be shifted endwise of the shaft.

Fastened to the shaft 77 outside of the side plate 34 is a knob 83 having suitably spaced apart on its periphery, the words 45 "Pay", "Certified" and "Cancelled". An indicator 84 attached to the side plate 34 of the casing coöperates with the wording on the knob to guide the operator in turning the shaft 77 and thereby the type carrier 74 50 to position the desired word type face in printing relation with the platen 27.

The movement of the type carrier 74 axially of the shaft 77 is imparted by downward movement of an operating handle 91. 55 This operating handle comprises side arms 92 and 93, Figs. 9 and 10, rigid respectively with hubs 94 and 95 fastened to the shaft 44. Formed on the lower end of the arm 93 of the operating handle is a segment 96, 60 Figs. 8 and 9, meshing with the teeth of a segment 97. The segment 97 works in a slot cut in an extension 98 of a casting 99 loose on the shaft 44 and having a slot at its rear end engaging the rod 47. The segment 97 is pivoted on a sleeve 100, Fig. 9,

extending through the extension 98 and resting at one end on a stud 101 fastened in the casting 99.

Pivoted on the stud 101 and held against movement in one direction by the end of 70 the sleeve 100 is an arm 102 carrying at its lower end a portion 103, Fig. 8, formed at right angles to the arm 102, the portion 103 in turn having a part 104 formed at a right angle thereto. Mounted in the arm 75 102 and part 104 is a rod 105 forming a support for an anti-friction roller 106 resting between peripheral flanges, previously mentioned, formed on or integral with the portion 76 of the sleeve 75. Surrounding 80 the sleeve 101 is a torsion spring 109 one end of which extends upward through a hole in an ear 110 formed on an arm 111 integral with the segment 97. The other end of the spring extends through a hole in an 85 ear 112, Fig. 10, formed on the portion 103 of the element carrying the antifriction roller 106.

From the foregoing, it is clear that when the operating handle 91 is pushed down, the 90 segment 97 will be moved counterclockwise, Fig. 10, and that this movement will be transmitted through the spring 109 to the element carrying the anti-friction roller 106 with the result that the type carrier 74 will 95 be moved toward the right as viewed in said figure. As before stated in a general way, this shifting movement of the type carrier may be interrupted at different points in the invariable stroke of the operating handle 91, this being permitted by the 100 resilient connection afforded by the spring 109.

In preparing the machine for operation, the handles 66 are operated to adjust the 105 type carriers ready to print the figures desired and the knob 83 is turned so as to set the type carrier 74 to print the desired word. When the operating handle 91 is depressed and the type carrier 74 slid to 110 the right, it will be stopped at the proper position to print the word in close relation to the digits of the amount. In order to do this it is, of course, necessary for the type carrier 74 to pass in front of some of 115 the digit type carriers and for this reason, the four higher order digit type carriers are cut away as shown at 115, Fig. 6, to provide a clearance. The units of dollars and the cents digit carrying elements may have 120 such clearances in order to reduce the number of parts necessary to be carried in stock but owing to the fact that they can not be turned to blank position, the units of dollars carrier will, when set at zero, always 125 have its lower end in the path of the sliding movement of the type carrier 74. If one of the type carriers above the units of dollars is turned to a printing position, its lower end will be moved into the path of 130

the shifting type carrier. Regardless of which of the type carriers is first in the path of the type carrier 74 when shifted, one of three pins 116 projecting from the type carrier 74 will engage one of the holes 117 thereby establishing a connection whereby the digit type carrier will assist in supporting the type carrier 74 when the printing impression is taken. Each of the digit 10 type carriers has formed in it a channel 118 to clear the two pins 116 for the word type not being printed from.

The machine in the drawings is intended to have its type and platen formed with co- 15 operating ridges and grooves after the manner shown and described in United States Letters Patent 793,249, issued June 27, 1905 to L. M. Todd. It is clear that such a construction of the type carriers and platen makes it desirable to prevent the shifting movement of the type carrier 74 from applying side stress to the digit type carrier; otherwise the type or platen might come together in incorrect alinement and one or 20 the other mutilated.

For this reason auxiliary mechanism is provided for limiting the shifting movement of the type carrier 74 before it can press against the side of the first positioned digit carrier. This auxiliary mechanism comprises four elements 121, Fig. 9, pivoted on the shaft 44 and guided in slots cut in the hub 122 of the casting or frame 99. Each of the elements 121 has a laterally extending portion 123, see also Figs. 8 and 6, carrying at their ends upwardly extending shoulders 124 engaged by the lower sides of the four higher order setting levers 66 when said levers are at their blank position. 35 Integral with each of the members 121 is a downwardly extending arm 125, Fig. 8. Stretched between these arms 125 and a rod 126 are light springs 127 tending to draw the arms 125 in the path of the right hand, 40 Fig. 10, peripheral flange of the member 76 on the type carrier sleeve 75. This movement of the arm 125 is, however, normally prevented by the latching pawls 71 holding the higher order type carriers locked in their blank positions. If a type carrier is moved from its blank to one of its printing positions, however, the tension on the spring 127 is released and the corresponding arm 125 will then be drawn in position to intercept 45 the flange member 76 and arrest movement of the type carrier 74.

As best shown in Figs. 8 and 9, the spring rod 126 is fastened in an arm 131 formed on the casting 99. This rod also serves to hold 50 one end of a spring 132 which is fastened at its other end to one arm of a bell crank 133 pivoted on a stud fastened to the side plate 34. The other arm of the bell crank 133 carries an anti-friction roller 134 riding

on the periphery of an element 135 fastened 65 to the shaft 77. The element 135 is so shaped that the bell crank 133 and the element 135 coöperate to retain the sleeve 75 and type carrier 74 in any one of the three positions to which it may be adjusted. 70

As before stated, the members comprising the arms 32 form part of the impression taking mechanism. For this purpose, the arms have formed on their forward ends two segments 141, see Figs. 6, 7 and 9. 75 Rigid with the arm 92 of the impression handle 91 is a segment 142 meshing with the teeth of the segment 141 on the left hand arm 32. Fastened to the shaft 44 near its right hand end is a segment 143, Fig. 9, 80 having teeth engaging teeth upon the right hand arm 32. As the operating handle 91 is fastened to the shaft 44 by means of its hubs 94 and 95 it is apparent that the segment 143 will coöperate with the right hand arm 85 32 in such a way that rocking movement of the shaft 44 by operation of the handle 91 will cause both ends of the shaft 44 and the parts thereon to have an equal extent of downward movement. All of the type faces 90 will, therefore, be brought down into engagement with the platen at the same time, thereby insuring uniform impression the full length of the printing line.

The pivoted casing and the parts therein 95 are normally held in elevated position by heavy torsion springs 144 at either side of the machine. One end of each spring is engaged under a cross bar 145 fastened at its ends in the side plates 34 and 35. The other 100 ends of the springs rest upon the horizontal portions 31 of the elements comprising the side arms 32. The upward movement of the pivoted casing is limited by extensions 146 of the side arms 32 engaging the elements upon which the segments 142 and 143 are formed. 105

Ink is applied to the type by a roll 151 which is normally held in a position in front of the printing line but which is, at the beginning of a printing operation, drawn rearward over the face of the type at the printing line to apply the ink. As the roll passes over the type it is resiliently pressed against the type, the resilient feature as before generally stated, preventing the setting of the type from being disturbed and also accommodating the roll to the type even though the roll may have become worn. 115

The ink roll 151 is carried by a shaft 152 120 journaled at its ends in arms 153 loose on a rod 154 supported in arms 155 swinging at either side of the machine from the rock shaft 44. Pivoted on the rod 154 are levers 156 having notches 157 engaging the ink 125 roll shaft 152. Wound around headed studs 161 projecting from the sides of the levers 156 are light springs 162. The for-

wardly extending ends of the springs 162 pass over the rod 154 and under a rod 163. The rearwardly extending portions of the springs 162 engage lugs 164 formed at the 5 rear of the levers 156 and are bowed to co-operate with studs 165 attached to the plates 34 and 35.

Projecting from the sides of the arms 155 are studs 166 engaging slots 167 formed at 10 such an angle in plates 168 fastened to the arms 32 that when the operating handle 91 is depressed and the shaft 44 moved downward, the arms 155 will be swung rearward, thereby carrying them and the ink roll devices supported thereby to the positions 15 shown in Fig. 6. As they pass to that position the bowed portions of the springs 162 acting against the studs 165 will press the ink roll into engagement with the type at 20 the printing line. When the operating handle is released, the springs 144 will raise the pivoted casing of the machine to its original position and, as it rises, the studs 166 and slots 167 will co-operate to return the ink roll 25 mechanism to the position in which it is shown in Fig. 7.

In describing the construction of the machine, it has been necessary incidentally to describe the operation at such length that 30 it is thought that the statement of operation customary at this point may be omitted.

While the illustrative machine shown and described is admirably adapted to fulfil the objects primarily stated, it is not the desire 35 to be limited to one form of embodiment as the invention is capable of embodiment in various forms, all coming within the scope of the claims which follow.

What is claimed is:

40 1. In a machine of the class described, the combination with digit type carriers and means for moving same to advance different digit type to a printing line; of a type carrier having a plurality of word type forms thereon, said carrier being adjustable to set any desired word type form at the printing line, and means for shifting the type carrier last mentioned into close printing relation with the highest order digit 45 type carrier to be printed from.

2. In a machine of the class described, the combination with a set of digit type carriers and means for moving them to set different digit type at a printing line, the digit type 55 carriers for the higher denominational orders being normally held with none of their type at the printing line; a movable type carrier having a plurality of word type forms thereon; means for moving the word 60 type carrier to position any desired word type form thereon in lateral alinement with the digit type at the printing line, and means for shifting the type carrier last mentioned into close printing relation with the

highest order digit type carrier having type 65 at the printing line, thereby preventing subsequent movement of the un-moved digit type carriers.

3. In a machine of the class described, the combination with a set of digit type carriers 70 one for each denominational order; means for operating one or more of the digit carriers to set up amounts of different denominational orders; a type carrier having a plurality of word printing type forms 75 thereon and means for operating same to set different word type forms in alinement with the amounts set up on the digit type carriers, and means for bodily shifting the word type carrier differentially toward the 80 digit carriers to extents depending upon the number of denominational orders in the amount to be printed by the digit type carrier.

4. In a machine of the class described, the combination with a set of rotatable digit type carriers; of a platen; means for rotating the digit carriers to set different digit type opposite the platen; a rotatable type carrier having a plurality of word type 90 forms thereon, said word type carrier being rotatable on a different axis than the digit type carrier; means for rotating the word type carrier to set different word type forms in alinement with the digit type to be 95 printed from; and means for shifting the word type carrier axially distances depending upon the number of denominational orders in the amount to be printed by the digit carriers.

100 5. In a machine of the class described, the combination with a set of centrally pivoted digit type carriers; a carrier for each denominational order; means for operating the type carriers to set up amounts of varying numbers of denominational orders; a type carrier having a plurality of word printing type forms thereon and rotatable on a different axis than the digit carriers; means for rotating the word type carrier to 105 set any desired word type form thereon in alinement with the amounts set up on the digit type carriers; and means for moving the word type carrier axially different extents depending upon the number of denominational orders in the amounts printed 110 whereby to print the desired word in juxtaposition to the highest digit.

115 6. In a machine of the class described, the combination with digit type carriers and setting means for moving a number of them varying according to the number of denominational orders in the amount to be printed; of a type carrier having a plurality of word type forms thereon and means for moving 120 same to set any desired word type form in alinement with the digit type to be printed from; means for shifting the type carrier 125

last mentioned into close printing relation with the highest order digit type carrier to be printed from; and means for establishing a supporting connection between the 5 shifting type carrier and said highest order digit carrier.

7. In a machine of the class described, the combination with a set of digit type carriers and manipulative devices whereby the setting of said carriers may be controlled to print amounts of different denominational orders; of a word printing type carrier provided with a plurality of word printing type forms; manipulative means for determining 10 the setting of the word printing type carrier; means controlled by the digit carrier manipulative devices for shifting the word printing type carrier laterally to extents varying according to the number of denominational orders in the amount to be printed; and means for establishing a supporting connection between the word type carrier and the highest order digit type carrier to be printed from.
8. In a machine of the class described, the combination with a pair of stationary segments; of an oscillating shaft and a handle rigid therewith for oscillating same; segments rigid with said shaft and meshing 20 with the segments first mentioned whereby oscillation of the shaft will cause bodily lateral movement of the shaft; and a printing couple brought together in printing engagement by said bodily lateral movement of 30 the shaft.
9. In a machine of the class described, a pair of stationary segments; a rock shaft and operating handle for rocking same; segments rigid on said shaft and meshing 35 with the stationary segments whereby rocking movement of the shaft will cause bodily

lateral movement of the shaft; a platen; and type carriers mounted on the rock shaft, said type carriers being carried into engagement with the platen by the bodily lateral 45 movement of the shaft.

10. In a machine of the class described, the combination with a platen, of a set of type carriers independently adjustable to set up items of different lengths opposite the 50 platen, a type carrier provided with a plurality of word type forms and adjustable to set the desired form opposite the platen and means for shifting said word type carrier toward the others to extents depending upon 55 the length of the item to be printed.

11. In a machine of the class described, the combination with a platen, of a set of type carriers independently adjustable to set up items of different lengths opposite the 60 platen, a type carrier provided with a plurality of word type forms and adjustable to set the desired form opposite the platen, means for shifting the word type carrier laterally toward the other carriers, and stops 65 controlled by said other carriers for differentially limiting said shifting movements.

12. In a machine of the class described, the combination with a set of type carriers and manipulative devices whereby the setting of said carriers may be controlled to print amounts of different lengths, of a word printing type carrier provided with a plurality of word printing type forms and manipulative means for determining the setting of same, means for shifting said word type carrier into the paths of unset type carriers and means whereby the shifting of the word type carrier will lock same to the left-hand set type carrier.

MAGNUS H. JOHANSON.
